(57) **CLAIM**

The ornamental design for a camera, as shown and described.

DESCRIPTION

FIG. 1 is a front, top, left perspective view of a camera;

FIG. 2 is a front elevational view thereof;

FIG. 3 is a rear elevational view thereof;

FIG. 4 is a bottom plan view thereof;

FIG. 5 is a top plan view thereof; and,

FIG. 6 is a left side elevational view thereof, the right side elevational view being a mirror image of the elevational view shown.

The broken lines in the drawings depict environmental subject matter only and form no part of the claimed design.
